(57) CLAIM

I claim the ornamental design for a combination grill, as shown and described.

DESCRIPTION

FIG. 1 is a front perspective view of a combination grill.

FIG. 2 is a front elevational view of the combination grill depicted in FIG. 1.

FIG. 3 is a rear elevational view of the combination grill depicted in FIG. 1.

FIG. 4 is a top plan view of the combination grill depicted in FIG. 1.

FIG. 5 is a bottom plan view of the combination grill depicted in FIG. 1.

FIG. 6 is a left side elevational view of the combination grill depicted in FIG. 1; and,

FIG. 7 is a right side elevational view of the combination grill depicted in FIG. 1.

The broken lines in the drawings illustrate portions of the combination grill that form no part of the claimed design. The patterned grip portions of the central handles are shown in broken lines and form no part of the claimed design.

1 Claim, 7 Drawing Sheets
